VEHICULAR PARKING INSTALLATION

William P. Brower, Glen Rock, and Walter I. Gadkowski, Irvington, N.J.

Application December 11, 1948, Serial No. 64,812

2 Claims. (Cl. 20—1.13)

1

This invention relates to vehicular parking and provides an improved vehicular parking installation of greater vehicle capacity for a given ground area than has been attained heretofore except in garage buildings. The parking installation of the invention achieves such increase in capacity by providing for parking on two levels, with parked vehicles one above the other, but does so without incurring the same high cost that is involved in building a multi-story parking garage.

The usual outdoor parking lot in use today is a substantial flat piece of ground on which automobiles or other vehicles are parked in rows with aisles or roadways between them. The amount of ground space available for parking vehicles in this manner, especially in crowded metropolitan districts, is grossly insufficient to meet the requirements brought about by the continually increasing volume of vehicular traffic. Heretofore the only solution actively developed to meet the parking problem of congested districts has been the construction of multi-storyed parking garages, either above ground or below. This solution is effective for greatly increasing the vehicle parking capacity of a given ground area, but has the serious disadvantage of being extremely costly, not only for initial construction but also for maintenance and because of high metropolitan property taxes.

The present invention provides a solution to the parking problem in congested centers that in effectiveness is substantially equivalent to the construction of a two-story parking garage, but which is very much less costly to build and on which maintenance costs are substantially no greater than on an outdoor parking lot of equal capacity. Basically the parking installation of the invention comprises a series of parallel roadways spaced apart from centerline to centerline by a distance approximately equal to the width of one roadway plus the length of a vehicle to be parked. A parking strip is provided on each side of each roadway, each strip being of a width approximately equal to the length of a vehicle to be parked, so that a series of vehicles may be parked side by side on each side of each roadway at a right angle to the length of the roadway. In order to enable the provision of such parking strips on both sides of each roadway, with the roadways spaced as closely together as specified, the parking strip on one or both sides of one roadway is spaced vertically directly above the adjacent parking strip alongside the neighboring roadway. The vertical spacing distance is made

2

greater than the height of a vehicle to be parked so that a vehicle on the lower parking strip may be driven under the strip above it. Such vertical spacing of adjacent parking strips is conveniently achieved in accordance with the invention by inclining the parking strips, and in some cases the roadways too, laterally about 12°, more or less, to the general plane of the parking installation. The parking strip dipping downwardly from one roadway forms a lower-level parking strip underlying the upwardly extending upper-level parking strip of the adjacent roadway. It is also possible to attain the requisite vertical spacing between parking strips by building up alternate roadways to a vertical height above the intervening roadways and lower-level parking strips that is greater than the height of a vehicle to be parked. This construction is more expensive than the use of inclined parking strips, but has the advantage that the vehicles are parked horizontally.

Construction of the new parking strip on a ground-level plot is largely achieved by simply regrading the ground to form the roadways and the lower-level parking strips. The only construction work required apart from regrading is the erection of the upper-level parking strips, which must be supported above the lower-level parking strips, and of such retaining walls as are necessary. The new parking installation is admirably adapted to hillside areas which heretofore have been deemed unsuitable for permanent parking facilities. The nature of the invention is such that on hillside ground a series of horizontal parking terraces are readily provided without sacrifice of the economical use of ground area that characterizes the invention. The invention is also well-adapted to providing parking facilities on rooftops of large public buildings. The uneconomical use of space characteristic of heretofore known outdoor parking installations has made it impractical to provide for parking atop buildings, but the space economy of the new parking installation makes it feasible to employ building roofs for parking purposes.

Several embodiments of the invention illustrating its adaptability to a wide variety of local conditions are shown in the accompanying drawings, in which:

Fig. 1 is a plan of a portion of a parking installation according to the invention;

Fig. 2 is a section through the parking installation of Fig. 1, taken substantially along the line

55—2—2 of Fig. 1;

Fig. 3 is a plan of a portion of a parking installation according to the invention;

Fig. 3 is a plan of a modified form of parking installation according to the invention;

Fig. 4 is a section through the installation shown in Fig. 3, taken substantially along the line 4—4 of Fig. 3;

Fig. 5 is a vertical section through a portion of another modification in which the new parking installation is adapted to a building roof; and

Fig. 6 is a vertical section through a portion of a further modification in which parking surfaces are horizontal.

Fig. 1 shows a highway or city street 10 connected by approaches 11 to a parking installation 12 constructed in accordance with the invention. This installation comprises a series of parallel roadways 13 and 14 which are spaced apart from centerline to centerline by a distance A approximately equal to the width of one roadway plus the length of a vehicle to be parked. An access road 15 constructed at right angles to the roadways 13, 14 connects with each of them and with the approaches 11 so that a vehicle from the street may be driven into any one of the roadways.

Turning now to the sectional view of the installation shown in Fig. 2, it is seen that a lower-level parking strip 16 adjoins each side of each alternate roadway 13. The parking strips 16 extend substantially the full length of the roadways they adjoin, and slope laterally downwardly therefrom at an angle of about 12° to a horizontal plane indicated by the line L. These lower-level parking strips are easily formed by simply regrading the ground from its original horizontal grade line L. The material excavated in forming the downwardly dipping parking strips 16 is used to build up the roadways 13 and 14 above the original grade line. The parking strips 16 are of a width substantially equal to the length of a vehicle to be parked, so that any such vehicle may be driven along a roadway 13 to an unoccupied portion of a lower-level parking strip and may then be turned from it and parked on the parking strip at a right angle to the length of the roadway in a row with other parked vehicles. The lower-level parking strips 16 adjoining each alternate roadway 13 terminate along lines underlying the side edges of the adjacent (intervening) roadways 14, as of course they must with the roadways spaced apart the distance specified and with the parking strips being of the width specified.

In order to provide for parking vehicles along the sides of the intervening roadways 14, a pair of upper-level parking strips 17 adjoins the side edges of each of these roadways. The upper-level parking strips 17 are inclined upwardly from the roadways 14 at an angle of about 12° to the horizontal, and directly overlie the lower-level parking strips 16. The upper-level parking strips may be reinforced concrete platforms as shown in Fig. 2, supported at their outer edges on concrete columns 18, although of course other structural materials and arrangements may be used in their construction.

Because of the lateral inclination of the parking strips 16 and 17 to the horizontal, they are spaced apart vertically by a distance greater than the height of a vehicle to be parked (e. g. an automobile 19). An inclination of about 12° to the horizontal is particularly advantageous because it results (with the roadway centerlines all lying substantially in a common plane) in the necessary vertical spacing of the upper-level

from the lower-level parking strips for vehicles having the ratio of length to height that characterizes most automobiles now in use. For example, with this degree of inclination, and with

5 roadways and parking strips each about twenty feet in width, a clear space of six to seven feet between upper and lower parking levels is achieved with the parking strips dipping laterally at an angle of about 12° to the horizontal.

10 Automobiles can be maneuvered without great difficulty to and from parking strips inclined to this degree.

The complete parking installation generally includes retaining walls 20 to support the roadways 14 from which the upper-level parking strips 17 are served. Drains 21 are provided at the low side edges of the lower-level parking strips 16 to carry away rain water and melted snow, and a similar grating-covered storm drain may be 15 provided along the centerline of the roadways 14. A guard wall 22 is provided along the outer side edge of each of the upper-level parking strips 17 where it overlies the side edges of the neighboring roadways 13. All roadways and the 20 lower-level parking strips may be surfaced with concrete or macadam as indicated in Fig. 2.

25 It is evident that the parking installation just described about doubles the parked-vehicle capacity of a given plot of ground, for the vehicles 30 are parked in two levels one above the other. This result is attained largely by regrading the ground. The only construction necessary is in the building of the upper-level parking strips and their supporting piers, and such retaining walls as may be necessary. Such construction is very much less expensive than would be required to build a two-story parking garage, which is the only way heretofore known for achieving equal parking capacity on a given ground area.

35 It has been mentioned above that parking installations according to the invention are admirably suited for adaptation to hillside plots such as have heretofore been considered unsuitable for parking purposes. A hillside parking 40 installation in accordance with the invention is shown in Figs. 3 and 4. Here a highway or street 25 is connected by an approach 26 to an access road 27 forming a part of the hillside parking installation 28. The access road connects with each 45 of a series of roadways 29 extending from it at right angles.

45 The construction of the parking installation 28 is perhaps most clearly seen by referring to the vertical section shown in Fig. 4. The hillside plot is regraded from its original sloping ground line S by making cuts into the hillside to form a series of lower-level parking strips 30. The width of these strips is about equal to the length of a vehicle to be parked. The 50 material excavated from these cuts is used in constructing the horizontal roadways 29. Thus there are formed a series of horizontal terraces spaced apart from roadway centerline to roadway centerline by the distance A (Fig. 3) equal approximately to the width of one roadway plus the length of a vehicle to be parked. The roadways are constructed so that their centerlines lie horizontally and all in a common plane that is parallel to the original grade slope of the hillside (indicated by the line S); and the angle 55 between this common plane and the plane of each roadway surface 29 and lower-level parking strip 30 is advantageously about 12°. This is equivalent to inclining the roadway 29 and the lower-level parking strip 30 laterally at an

angle 12° to the horizontal in the case of a parking installation built on horizontal ground.

To achieve the increased parking capacity per unit of ground area that characterizes the invention, an upper-level parking strip 31, elevated from the hillside, is constructed along the side of each roadway 29 opposite the side adjoining the cut by which the lower-level parking strip is provided. In the construction shown in Fig. 4, the upper-level parking strips 31 are platforms of steel grating or reinforced concrete carried by steel cantilever supports 32. Retaining walls 33 are provided for supporting the roadways and the upper-level parking platform cantilevers. Guard rails 34 are arranged along the outer side edge of each upper-level parking strip. The upper-level parking strips 31 directly overlie the lower-level parking strips 30, so that vehicles are parked one above the other, and the same economy in use of the ground area is achieved as in the case of the parking installation shown in Figs. 1 and 2.

When the slope on the hillside is about 12° to the horizontal, the parking strips and roadway surfaces may be horizontal, as shown in Fig. 4, with each upper-level parking strip spaced vertically from the adjacent lower-level parking strip by a distance just enough greater than the height of a vehicle to be parked to permit driving such vehicle under the upper-level strip. If the hillside slope is greater than 12°, the same horizontal arrangement of roadway and parking strip surfaces may be attained with still greater vertical spacing between the upper- and lower-level parking strips. If the hillside slope is less than about 12°, then adequate vertical spacing between the upper- and lower-level parking strips may be attained by inclining the plane of the roadway and parking strip surfaces enough so that an angle of at least about 12° between these planes and the original slope of the hillside (or the common plane of the roadway centerlines) is maintained. The extreme inclination of the roadway and parking strip surfaces to the horizontal will of course be 12° when the installation shown in Figs. 3 and 4 is employed on a horizontal ground surface.

An embodiment of the invention in an installation for rooftop parking is shown in Fig. 5. In this modification the building roof is of typical factory saw-tooth construction by which a series of parallel, laterally inclined roof surfaces are defined. These roof surfaces are supported on inclined trusses 35 which in turn are carried on building frame columns 36. The saw-tooth roof structure defines a plurality of long relatively narrow surfaces. The longitudinal centerlines of the inclined roof surfaces are horizontal (in a direction perpendicular to the plane of Fig. 5), and are spaced apart by the distance A approximately equal to the width of a roadway plus the length of a vehicle to be parked. The lateral inclination of these roof surfaces is, as shown in Fig. 5, about 12° to a horizontal plane (indicated by the line H). The high side portion 37 of each of these inclined roof surfaces (to the right of the centerline as seen in Fig. 5) forms a roadway, and the low side portion 38 (to the left of the centerline) forms a lower-level parking strip which is about equal in width to the length of a vehicle to be parked. A horizontal access road (not shown) is built along the side of the building to give access to each of the roadways 37. A vehicle elevator or ramp (not shown) is provided to gain the access road from the ground level.

A long, relatively narrow, upper-level parking platform 39 (its narrow dimension is shown in cross section in Fig. 5) is built out from the high side edge 40 of each inclined roof surface throughout substantially its entire length, and extends upwardly therefrom at an angle of about 12° to the horizontal. This upper-level parking platform is shown in Fig. 5 as being made of steel grating supported on beams 41 and 42 which in turn are carried on columns 43. A guard rail 44 is erected along the outer edge of each upper-level parking platform 39. Grating-covered drains 45 are arranged along the low side edge of each of the roof surfaces to carry away rain water and melted snow. Windows 46 may be provided in the vertical sections between adjoining inclined roof surfaces to provide for lighting and ventilating the triangular spaces beneath the roof in case it is desired to make use of this space for storage purposes or otherwise.

As in the previously described embodiments of the invention, the upper-level parking platform directly overlies the lower-level parking strip, and is spaced therefrom by a vertical distance at least as great as the height of a vehicle to be parked. Vehicles are parked in two levels, thereby attaining maximum parking capacity on the rooftop space. Rooftop parking has not heretofore been attractive because rooftop space is limited in area and it has been economically impractical to provide rooftop parking for the limited number of vehicles which could be accommodated using heretofore conventional parking arrangements. By means of the present invention, which approximately doubles the parking capacity of rooftop space, the use of such space on factory buildings, auditoriums, etc., is much more attractive than heretofore.

A parking installation built on horizontal ground and in which all of the parking strips and roadway surfaces are themselves horizontal is shown in Fig. 6. In this modification each alternate parallel roadway 48 and the lower-level parking strips 49 which it serves are all formed horizontally on the same level. The intervening parallel roadways 50 are built up to any desired height (greater than the height of a vehicle to be parked) above the lower-level parking strips. This is most readily accomplished by excavating from the original ground line L' to form the lower-level roadways 48 and parking strips 49 and using the excavated earth to build up the intervening roadways 50 to the required height.

As in the installations previously described, the horizontal distance between centerlines of adjacent roadways 48 and 50 is about equal to the width of a roadway plus the length of a vehicle to be parked. To provide for parking along both sides of the raised intervening roadways 50, upper-level parking strips in the form of platforms 51 overlying the lower-level parking strips 49 are built out from the side edges of these roadways. The platforms 51 are supported at their outer edges on steel or concrete columns 52, or in any other suitable way. Guard rails 53 are provided along the length of the outer edges of the upper-level parking strips; and retaining walls 54 are employed to support the upper-level roadways 50.

Access roads running at right angles to the roadways 48 and 50 are advantageously built at a level about midway between the upper-level and lower-level parking strips, and are connected to the roadways by short ramps; or alternatively the access roads may have an undulating

surface that rises from about the level of one of the alternate lower-level roadways 48 to about that of the adjacent roadway 50, and then descends again to the next lower-level roadway.

The modification shown in Fig. 6 is more expensive to construct than the modifications previously described where the parking strips are arranged at an angle of about 12°, more or less, to the original ground line. It has the advantage, however, that parked vehicles are horizontal, and the vertical height between upper-level and lower-level parking strips is independent of any particular degree of slope.

It is of course apparent that a compromise between the horizontal construction shown in Fig. 6 and a construction using inclined parking strips, such as is shown in Figs. 2 and 5, is possible, by using a parking strip slope that is substantially less than the value of 12° (more or less) hereinbefore mentioned but greater than zero. In such a compromise arrangement, alternate roadways will be lower than the intervening roadways, but the vertical height between them need not be so great as is required in the modification shown in Fig. 6.

The parking installation of the invention may be used with advantage for other purposes than merely to provide for parking of unattended vehicles in crowded shopping, office, or amusement centers. There is a growing development of services designed to accommodate motorists who remain within their automobiles, of which the outdoor "drive-in" moving picture theater is one example. The parking installation of the invention is very well adapted to accommodate vehicles wherever such services are offered. In a "drive-in" theater, for example, the new parking installation is of advantage to the theater operator because it reduces the ground area required for a theater of desired automobile capacity, and is of equal advantage to the theater patron because it provides increased parking space in close proximity to the moving picture screen.

The embodiments of the invention specifically described herein and shown in the accompanying drawings are merely illustrative of the ways in which the basic features of the invention may be adapted to meet the requirements of local conditions. Numerous modifications and adaptations of the invention may be made without departing from these basic features, and indeed some such modifications will be required more often than not in order to combine economy with effective use of the invention in designing each individual installation.

We claim:

1. A vehicular parking installation comprising a series of parallel roadways spaced apart from

centerline to centerline by a distance approximately equal to the width of one roadway plus the length of a vehicle to be parked and with their centerlines lying substantially in a common plane, each roadway being inclined laterally at an angle to said common plane, a lower-level parking strip of width approximately equal to the length of a vehicle to be parked adjoining the low side of each roadway and sloping downwardly therefrom at an angle to about 12° to said common plane, an upper-level parking strip of approximately the same width as the lower-level parking strips adjoining the high side of each roadway and sloping upwardly therefrom at an angle of about 12° to said common plane, each upper-level parking strip directly overlying the adjacent lower-level parking strip and being spaced vertically therefrom by a distance greater than the height of a vehicle to be parked, and an access road substantially perpendicular to said roadways lying substantially in the common plane of the roadway centerlines and connecting with each roadway.

2. A vehicular parking installation atop a building comprising a saw-tooth building roof defining a plurality of long relatively narrow surfaces, the longitudinal centerlines of said surfaces being substantially horizontal and said surfaces being each inclined laterally at an angle of about 12° to the horizontal, the high side portion of each of said surfaces forming a roadway and the low side portion thereof forming a lower-level parking strip, and a long relatively narrow upper-level parking platform adjoining the high side edge of each of said surfaces throughout substantially the entire length thereof and projecting therefrom upwardly at an angle of about 12° to the horizontal, said upper-level parking platforms and said lower-level parking strips each being of substantially equal widths, and each of said upper-level parking platforms being supported directly above the adjacent lower-level parking strip and being spaced vertically therefrom by a distance greater than the height of a vehicle to be parked.
